COMBINED HANDLE STICK AND CUP COVER FOR FROZEN CONFECTIONS OR THE LIKE

Nelson R. Coleman, 2301 Ravenviiew Road,
Timonium, Md.

Filed May 24, 1961, Ser. No. 65,314

Term of patent 14 years

(Cl. D44—1)

FIG. 1

FIG. 2

FIG. 3

FIG. 4

FIG. 5

FIG. 1 is a perspective view of a combined handle stick and cup cover for frozen confections or the like showing my new design;

FIG. 2 is a side view thereof;

FIG. 3 is a side view taken 90° to that of FIG. 2;

FIG. 4 is a top view thereof; and

FIG. 5 is an elevational view similar to FIG. 2 with a cup shown in broken lines for illustrative purposes only.

I claim:

The ornamental design for a combined handle stick and cup cover for frozen confections or the like, as shown and described.
